VIBRATION-ABSORBING MOUNTING FOR
SEPARATORFrederic P. Gooch, North Miami Beach, Fla., assignor to
Ametek, Inc., New York, N.Y., a corporation of
DelawareFiled Feb. 12, 1962, Ser. No. 172,492
1 Claim. (Cl. 233—24)

The present invention relates to centrifugal separators, and particularly to a vibration absorbing mounting for such separators.

Centrifugal separators employ a basket that is rotated at high speeds and into which is fed a slurry containing a material of one density that is adapted to be separated from material therein of another density. It frequently occurs that the material of greater density is a solid or of such density that when separated, it produces unbalanced loads within the basket, thereby causing excessive vibrations to be produced which, at high basket speeds, may even cause destruction of the apparatus.

The principal object of this invention is to provide a centrifugal separator and a vibration-absorbing mounting therefor which will be inexpensive and yet effective to absorb the vibrations incident to the operation of centrifugal separators.

Another object of the invention is to provide a centrifugal separator and vibration-absorbing mounting therefor wherein the basket of the centrifugal is fixed to a vertically disposed spindle.

Still another object of the invention is to provide such a centrifugal separator in which the separator is supported on a base plate having radial as well as axial vibration-absorbing mountings between the plate and separator as well as between the plate and the plate-supporting means.

In one aspect of the invention, a basket may be fixed to one end of a vertical spindle that is journaled within relatively widely spaced, aligned, antifriction bearings within a vertical pedestal. The spindle may extend beyond the pedestal and have a driving pulley or other power input means connected to its extended end opposite that fixed to the basket.

The basket may include thin, closely spaced, nested conical members forming what is known in the trade as a "disk clarifier." Peripherally spaced exit means may be provided in the outer wall of the basket for passing the solids or dense residue that accumulated about the inner periphery of the basket. A non-rotatable slurry feed means may be provided axially of, and above the basket for supplying material to be treated to the basket substantially along its axis of revolution. As the basket rotates, the slurry is thrown outwardly, causing the more dense material thereof to accumulate along the inner periphery of the basket, and the action of the thin conical members causes the effluent to move upwardly between them to an overflow.

In another aspect of the invention, the vertical pedestal journaling the vertical spindle may be fixed to a base plate which latter may be supported by a frame through the agency of prestressed, flexible, vibration-absorbing means that is capable of absorbing both radial and axial vibrations set up by the rotation of the basket when unbalanced loads are encountered.

In still another aspect of the invention, the supporting frame may include a foot at each corner thereof which foot may include prestressed flexible vibration-absorbing material capable of absorbing not only radial but axial vibrations incident to the operation of the separator.

The above, other objects and novel features of the invention will become apparent from the following specification and accompanying drawings which are merely exemplary.

2

In the drawings:

FIG. 1 is a top plan view of a separator and mounting therefor to which the principles of the invention have been applied;

FIG. 2 is a sectional elevational view taken substantially along line 2—2 of FIG. 1;

FIG. 3 is a sectional plan view, on a reduced scale, taken substantially along line 3—3 of FIG. 2; and

FIG. 4 is a sectional elevational view taken substantially along line 4—4 of FIG. 1.

Referring to the drawings, and particularly to FIGS. 1 and 2, the principles of the invention are shown as applied to a disk clarifier type of centrifugal separator including a basket 10 having a central wall 11 of a modified conical form, flaring outwardly near the bottom of the basket. Another modified hollow, conical member 12, concentric with the wall 11, may provide an annular passage 13 between the wall 11 and member 12. Ribs 14 and 15 at spaced intervals about passage 13 may join the member 12 to the wall 11.

A hollow frusto-conical member 16 may be attached to the outer wall 17 of the basket 10 by ribs 18. A nested stack of thin conically shaped members 19 separated by ribs 19' may be located between the members 12 and 16, as is common in separators of this type.

The inner wall 11 of basket 10 may be provided with a tapered central passage 20 adapted to fit onto the tapered end 21 of a vertically disposed spindle 22. The spindle 22 may be journaled in spaced antifriction bearings 23 and 24 within a vertical pedestal 25. Spaced ribs 26 fixed to pedestal 25 are also fixed to a plate 27 that may be rigidly bolted to a base plate 28. The base plate 28 is mounted in a peculiar fashion on a frame 29 in a manner to be described later.

The spindle 22 extends beyond the plate 28 and is shown as supporting a pulley 30 at the end thereof opposite that to which basket 10 is fixed. A belt or other driving means 31 may connect pulley 30 to a corresponding pulley 30' on the output shaft of a motor 32 that is mounted on the frame 29 and which may include an adjustable mounting such as rotatable threaded sleeves 33 that engage non-rotatable threaded studs 34 fixed to the base of the motor 32 for adjusting the tension of the belt 31.

From the foregoing it is evident that the basket 10 is mounted at one end of a relatively long spindle 22 and that when unbalanced loads develop within it, its center of gravity is displaced from the axis of rotation of the spindle 22. At high speeds of the basket 10, these unbalanced forces tend to cause the spindle 22 to gyrate or wobble in a manner to produce radial as well as axial vibrations.

The frame 29 may include a top plate 35 having a hole 36 therein through which projects the lower end of spindle 22. Between the plates 28 and 35 may be located a plurality of resilient mounting elements 37. While as few as three such mounting elements may be employed, spaced 120° about the axis of spindle 22, in the embodiment disclosed eight such elements are shown. The elements 37 may comprise a metal sleeve 38 that acts as a core and is bonded to the internal wall of a cylindrical member 39 having a flange 39' and made from a resilient material such as rubber, neoprene or the like. The length of the cylindrical member 39 is substantially greater than that of the metal sleeve 38. A bolt 40 may extend through the sleeve 38 and a nut 41 may be threaded onto the bolt 40 with a washer 42 between it and the end of the cylindrical member 39. When the nut and bolt are tightened, the portion of the resilient cylinder member 39 beyond the end of the metal sleeve 38 is caused to expand into a flange 43 at the end of member 39 opposite flange 39'.

The plate 35 of frame 29 may include a skirt portion

44. Referring to FIG. 4, the skirt 44 may be attached to a foot member 45 at each corner of plate 35. Each foot member 45 may comprise a metal disk 46 to which is threaded or otherwise fastened a rod 47. Resilient disk means 48 may surround rod 47 and seat on disk 46. The disk means 48 may be made from a sheet of a vibration and damping material such as a bonded mixture of cork and rubber. One such material is made by The Korfund Company in Westbury, Long Island, New York. A flanged disk 49 may rest on the disk means 48, and a cylindrical member 50 may be welded or otherwise fastened to the disk 49. The upper end of the cylinder 50 may be provided with a counterbore forming a shoulder 51 on which may rest a metallic disk 52. One or more sheets of vibration damping material 53 similar to that of disk 48 may rest on disk 52, and another metal disk 54 may rest on the sheet 53. The rod 47 may extend upwardly through and beyond the disk 54 and have nut means 55 threaded thereto for prestressing the vibration damping sheets 48 and 53. A cover 56 may be mounted on the top of cylinder 50 to prevent unauthorized adjustment of the nut means 55. The plate 35 may have arcuate cut-out areas at each corner thereof for receiving the feet 45, and the skirt 44 may rest on, and be attached to the flanged disks 49 of each foot.

Referring again to FIG. 2, a slurry or mixture of material to be treated may be continuously fed through a line 57 into the basket 10 descending through the space between the inner wall 11 of basket 10 and the conical member 12 while the basket is rotating at operating speed which may be in the order of about 6,000 r.p.m. The solids or more dense portion of the slurry is centrifugally thrown radially outwardly toward the outer wall 17, passes through nozzles 58 and is collected in a stationary housing 59, gravitating through a duct or outlet 60. The less dense portion of the slurry flows upwardly between the thin nested conical members 19 and is discharged through outlets 61 leading to a stationary outlet 62.

Unbalanced loading of the basket 10 may tend to cause the spindle 22 to rock or wobble about the lower bearing 24 which sets up radial as well as axial vibrations. The resilient mountings 39, which are in compression axially as well as radially, damp and absorb both the axial and radial vibrations set up by the rotating mass. Furthermore, any vibrations that pass beyond the mountings 39 into the frame 29 are absorbed and damped by the pre-stressed resilient isolating sheets 48 and 53 within each of the feet 45 at the corners of the frame 29.

Although the various features of the invention have been shown and described in detail to fully disclose one embodiment of the invention, it will be evident that changes may be made in such details and certain features may be used without others without departing from the principles of the invention.

What is claimed is:

In a centrifugal separator, a base plate; a pedestal mounted on, and located at the center of said base plate; a frame for supporting said base plate and pedestal, said frame acting as a floor support for said separator; a spindle extending axially through said pedestal; spaced antifriction bearings within said pedestal for journaling
